US00D714029S

(12) **United States Design Patent**
Wexler(10) **Patent No.:** **US D714,029 S**
(45) **Date of Patent:** **** Sep. 30, 2014**(54) **PANEL FOR LOWER BODY GARMENT**(71) Applicant: **Michelle L. Wexler**, Highland Park, IL (US)(72) Inventor: **Michelle L. Wexler**, Highland Park, IL (US)(73) Assignee: **The Underwares Group, LLC**, Highland Park, IL (US)(***) Term: **14 Years**(21) Appl. No.: **29/449,529**(22) Filed: **Mar. 15, 2013****Related U.S. Application Data**

(63) Continuation-in-part of application No. 13/211,925, filed on Aug. 17, 2011.

(51) **LOC (10) Cl.** ..... **02-02**(52) **U.S. Cl.**USPC ..... **D2/853**(58) **Field of Classification Search**

USPC D2/731, 738, 742, 712, 853; 2/79, 227, 2/228, 238, 267, 401

See application file for complete search history.

Primary Examiner — Rashida Johnson(74) *Attorney, Agent, or Firm* — McAndrews, Held & Malloy, Ltd.(57) **CLAIM**

The ornamental design for a panel for lower body garment, as shown and described.

DESCRIPTION

The sole FIGURE is a top rear perspective view of a panel for lower body garment showing my new design. The broken lines represent the portions of the design, which form no part of the claim. Undisclosed features form no part of the claimed design.

1 Claim, 1 Drawing Sheet# US D714,029 S
